WINDSHIELD CLEANER CONTROL MECH-
ANISMErwin C. Horton, Hamburg, N. Y., assignor to
Trico Products Corporation, Buffalo, N. Y.

Application March 22, 1935, Serial No. 12,522

2 Claims. (Cl. 121—142)

This invention relates to an automatic windshield cleaner and primarily to an improved control for the motor of the same.

The present day motor vehicle is equipped with a windshield cleaner which is mounted within the fabricated structure of the body so that any regulation in the speed of operation of the cleaner necessitates the removal of a body panel and requires the services of a mechanic.

10 The object of the present invention is to provide a windshield cleaner which is more satisfactory in operation. It comprehends bringing the regulation of the cleaner speed under the control of the motorist, so that he may adjust the 15 speed of operation of the wiper back and forth across his line of vision to suit his particular desire; and further, the invention comprehends the embodiment of such regulator in a common control unit with the means for rendering operative 20 and inoperative the cleaner.

In the drawing depicting one embodiment of the invention, Fig. 1 is a fragmentary showing in plan of a windshield cleaner embodying the present invention:

25 Fig. 2 is a front elevation thereof, and

Fig. 3 is a detailed sectional view of the regulator or governor.

Referring more particularly to the drawing wherein is illustrated by preference a fluid operated windshield cleaner of a well-known construction, the numeral 1 designates the cleaner motor embodying a piston (not shown) movable back and forth in a chamber by a fluid pressure differential which is alternately reversed through 30 valve mechanism contained in a housing 2, the mechanism being opened to a source of low pressure through a shut-off valve generally indicated at 3. Such a windshield cleaner motor construction is shown in Patent No. 1,840,233, granted January 5th, 1932 to Henry Hueber. According to the present disclosure the stem 4 of the shut-off valve 3 is connected to one arm of a bell crank lever 5 by a pin and slot connection 6. The bell crank lever, being pivoted at 7 on the 45 motor casing, has its opposite arm 8 extended to be rocked by the control hereinafter referred to.

Fluid communication between the shut-off valve and the source of suction or low pressure is established by passage 9 which leads through a speed regulator or governor member generally indicated at 10. This regulator may be of any suitable construction and is herein illustrated as comprising a casing having a chamber 11 into which passage 9 opens and from which leads a 50 second passage 12 through a valve seat 13, the

passage 12 being connected to the source of suction, such as the intake manifold of the motor vehicle engine, by suitable tubing. The chamber 11 is provided with a movable wall 14 which is subjected at its inner side to the low pressure influence in the chamber and at its outer side to the outside atmospheric pressure, such communication with the outside atmosphere being established through ports 15 in a cover plate 16. The movable wall is thus acted upon by a pressure differential and, when the pressure in the chamber 11 is of a predetermined low value, responds thereto by moving toward the valve seat 13 to throttle and restrict the passage therethrough. This results in the modification of the degree of 5 low pressure available at the control valve 3 for the operation of the windshield cleaner motor.

To insure a more accurate valve action by the movable wall, a valve plate 17 is interposed between the same and the valve seat, such plate 20 being adapted for movement with the movable wall toward the seat. The composite valve thus formed is urged away from the seat by a spring 18 which is conveniently disposed in the outlet passage 12 and bears at its outer end on the valve plate 17, while its opposite end is seated upon a regulating screw 19. This screw is threaded into the housing 10 of the regulator for adjustment and therefore, by turning the screw 19 clockwise or counter-clockwise, the tension of 30 the spring 18 will be correspondingly increased or decreased. The spring therefore will urge more or less upon the valve plate 17 to resist movement of the latter toward the seat 13. Consequently the pressure differential required to 35 throttle the suction passage through the regulator may be varied and determined to regulate the speed of the windshield cleaner for faster wiping or slower, as the motorist may desire.

The adjustment of the regulator, as well as 40 the on-and-off movement of the shut-off valve, is brought under a single control and rendered accessible to the motorist so that by a simple manipulation, the windshield cleaner may be started, stopped or regulated to the desired speed 45 of operation as the motorist may dictate. According to the present disclosure this control is illustrated as being of the remote type and embodies a push-pull wire 20 housed within a flexible armor 21 and provided at its outer end 50 with a knob or button 22 by which the wire may have longitudinal movement imparted thereto, as well as rotational movement.

Rotary movement of the wire is utilized to turn the regulating screw 19 and thereby adjust the 55

urge of the spring 18. To this end, the control wire is provided with a tubular end coupling or sleeve 23 which receives the outer end of the regulating screw 19 and is keyed thereto by a 5 radial pin 24 on the screw fitting into a longitudinal slot 25 in the sleeve. This arrangement connects the regulating screw to the wire for imparted rotational movement but permits axial or longitudinal movement of the wire independently of such screw for rocking the bell crank lever 5, 7. For this purpose the coupling member 23 is provided with an annular groove 26 to receive the outer end of the arm 8, which may be forked if desired, so that endwise movement to 10 the wire 20 will rock the bell crank lever and accordingly move the shut off valve 3 to a closed or open position. The outer end of the flexible armor 21 may be given substantial support from the motor casing by a bracket 27 or 15 it may be otherwise supported in an accessible position. The inner end of the flexible armor is secured to the motor casing by an anchor clip 28. This assemblage adapts the entire cleaner as 20 a unit for convenience in mounting and installation in the motor vehicle body.

In operation, the normal or in-position of the knob 22 preferably will be the shut-off position for the windshield cleaner. Therefore to start the cleaner in operation, it is simply necessary 25 to pull out on the control knob and thereby rock the bell crank lever clockwise, in Fig. 1, to open the shut-off valve 3. The cleaner operation may be adjusted faster or slower by simply turning the knob 22 clockwise or counter-clockwise until 30 the desired speed is obtained without disturbing the shut-off valve. The pin and slot connection permits lineal movement of the push-pull control 35 for actuating the shut-off valve and also lineal movement of the adjusting screw during rotation of the latter. Thus placing the two regulating instrumentalities under a single control which is readily accessible to the motorist, it is 40

obvious that the regulation of the cleaner operation will be more satisfactory to the particular motorist and that the changes in the operation readily may be accomplished.

What is claimed is:

1. A windshield cleaner unit having a motor with power shut-off means and speed regulating means, one of the means having a reciprocable actuating part and the companion means having a rotatable actuating part, a control common to both means whereby the cleaner may be regulated in its speed of operation as well as started and stopped therefrom, said common control embodying a rotatable member mounted for bodily movement, means connecting the member to the second actuating part for imparting rotational movement thereto, said connecting means permitting limited bodily movement of said member independently of the second actuating part and connected to the first actuating part for moving the latter during such bodily movement whereby the operation of the motor may be concurrently regulated and controlled, and means supporting the control from the motor for mounting and demounting as a unit therewith.

2. A windshield cleaner unit having a wiper operating motor with a power shut-off member and a speed regulating member, both of said members being mounted on said motor and one of said members being rotatable and the other reciprocable, a flexible push-pull control mounted also for rotatable movement, a pin and slot connection between said control and the rotatable member connecting the two elements for rotational movement and permitting relative lineal movement, and an armor for the flexible control for guiding the latter in its rotary and longitudinal movements, said armor being rigidly supported at both ends from the motor, whereby the unit may be mounted and demounted as an entirety.
